2,626,119 1/1953 Crosby ..... D6/518 X
2,678,184 5/1954 Erdody ..... D6/518 X

Primary Examiner—Brian N. Vinson

Attorney, Agent, or Firm—Harvey S. Hertz

[57] CLAIM

The ornamental design for a tissue dispenser, as shown and described.

DESCRIPTION

FIG. 1 is a top, front, and right side perspective view of a tissue dispenser showing my new design, the broken-line disclosure of a tissue box being for illustrative purposes only and forming no part of the claimed design; FIG. 2 is a top, rear, and left side perspective view thereof, with part of the housing shown rotated to a vertical position;

FIG. 3 is an enlarged front elevational view thereof; FIG. 4 is an enlarged rear elevational view thereof; FIG. 5 is an enlarged right side elevational view thereof, the left side being a mirror image of that shown; FIG. 6 is an enlarged top plan view thereof; and, FIG. 7 is an enlarged bottom plan view thereof.
